229,706

CARD GAME SCORE HOLDER FOR ATTACHMENT TO TABLE CORNER

Scott Lewis, 37 Shore Road, Ogunquit, Maine 03907

Filed Aug. 13, 1971, Ser. No. 171,788

Term of patent 14 years

Int. Cl. D21—01

U.S. Cl. D34—13 A

FIG. 1 is a perspective view of a card game score holder for attachment to a table corner showing my new design; and

FIG. 2 is a perspective view of the opposite side thereof. The two upright panels are transparent.

I claim:

The ornamental design for a card game score holder for attachment to table corner, as shown and described.

References Cited

UNITED STATES PATENTS

1,626,107	4/1927	Ullrich	248—226 A
2,049,855	8/1936	Meyer	40—16.6
2,171,350	8/1939	Anderson	40—16.6
2,691,837	10/1954	Gove	40—16.4

MELVIN B. FEIFER, Primary Examiner